UNITED STATES PATENT OFFICE

104,981

DESIGN FOR TERRARIUM OR THE LIKE

Fred Munz, Jamaica, N. Y.

Application April 19, 1937, Serial No. 68,876

Term of patent 14 years

To all whom it may concern:

Be it known that I, Fred Munz, a citizen of the United States, residing in Jamaica, city of New York, county of Queens, and State of New York, have invented a new, original, and ornamental Design for a Terrarium or the like, of which the following is a specification, reference being had to the accompanying drawing, forming part thereof.

Figure 1 is a side view of a terrarium embodying my design and

Figure 2 is a perspective view thereof.

The characteristic feature of the design consists of a group of predetermined plants enclosed within a glass bowl of the configuration illustrated. The plants within the bowl form a permanent part of the design.

I claim:

The ornamental design for a terrarium or the like as shown and described.

FRED MUNZ.
